TYPE BAR CUSHIONING PAD

Giuseppe Prezioso, Yverdon, Switzerland, assignor
to E. Paillard et Cie S. A., Yverdon, Switzerland, a corporation of Switzerland

Application August 7, 1941, Serial No. 405,874
In Switzerland September 2, 1940

4 Claims. (Cl. 197—42)

Typewriters of modern type must fulfill a number of requirements which are often in contradistinction with one another such for example as noiselessness and speed. One of the principal causes of noise or rattle in a typewriter is due to the impact of the type bars upon their carrier. The noise thus produced naturally increases as the touch grows faster. In order to eliminate such noise, it has been previously proposed to line the carrier for the type bars with a coating of a resilient material such as indiarubber, felt or the like. However, the more resilient the lining thus fitted or in other words the more capable it is to obviate the noise produced by the sharp impact of the type bars as they fall back to their position of rest, the greater their tendency to rebound. This rebounding action soon grows large enough to make it impossible to continue to typewrite even at normal speed as the thus rebounding type bars soon become entangled. In view of this, a compromise solution was adopted hitherto consisting in either sacrificing rapidity of operation to noiselessness or conversely noiselessness to rapidity depending upon the kind of typewriter and the purpose for which it is intended to be used. It has also been proposed to support the lining made of resilient material by elastic members permitting said lining to be shifted longitudinally. However, the result that was thus sought failed to be attained. Moreover, linings comprising a metal core imbedded in a pliable or elastic covering did not meet the requirements either.

An object of the present invention is to provide an improved pad or cushion for the type bars of typewriters, said pad having such a construction as to substantially attenuate the noise or rattle that they would otherwise produce when swinging back to their position of rest after striking the ribbon against the paper sheet on the platen without, however, rebounding to any appreciable extent and giving rise to any risk of the type bars becoming entangled or gripping one another.

Another object of the invention is to provide an improved impact-taking pad or cushion of this character having such a structure as to lend itself to repeated resilient distortions without losing its operative shape and cushioning capacity even after prolonged use.

With these and such other objects in view as will incidentally appear hereinafter, the invention consists in the novel construction, combination and arrangements of elements that will now be described in detail with reference to the ac-

companying drawing which illustrates embodiments of the invention.

In the drawing:

Figure 1 is a diagrammatic front view showing a form of the cushioning pad in operative position on its carrier, the type bars of conventional shape whose impact must be taken by this pad not being illustrated.

Figure 2 is a sectional view on the line II—II of Fig. 1.

Figure 3 is a view similar to Fig. 1 showing an alternative constructional form of the pad and carrier assembly.

Figure 4 is a sectional view on the line IV—IV of Fig. 3.

As illustrated in Figs. 1 and 2, an upstanding arcuate carrier member or plate 1 made for example of sheet metal and rigidly secured in any approved way to the typewriter frame (not shown) is provided with end eye-shaped brackets 2 and with a trough-shaped portion 3 in the middle of its length. The brackets 2 are adapted to girdle and clamp the pad or cushion 4 at or adjacent its respective ends while leaving it free to resiliently yield over substantially the whole of its length. The purpose of the trough-shaped portion 3 is merely to guide the pad and to hold it in the required location so as to prevent the same from swinging or swaying. The pad 4 is advantageously constituted by an elongated body of tubular or hose-like shape made of any suitable pliable or supple substance.

In the alternative constructional form shown in Figs. 3 and 4, the elongated pad or cushion 4 extends beyond the ends of the carrier member 1 and the latter is fitted with trough-shaped brackets or clips 5 which do not girdle the pad 4 around the whole of its peripheral outline. Proper attachment of the pad in the holding brackets or clips 5 may be performed by any suitable means and particularly by any convenient procedure capable of causing their matching or contiguous surfaces to remain adherent or coalescent, for example by a curing, cementing, sticking or vulcanizing process, as is well known in the art. In this constructional form, the elongated tubular or hose-like pad 4 is internally fitted by any of the procedures above mentioned with an arcuate rod-like or wire-like core 6 having the same radius of curvature of the pad, said rod also having stiffening properties and a cross sectional area smaller than that of the hollow portion of the pad.

Advantageously the core 6 is a pre-shaped metal rod, rope or wire while the tubular pad 4

may be made either of a homogeneous material such as pure rubber or latex or else of a composite or laminated material such for example as natural or artificial rubber in which canvas or buckram is imbedded or inlaid, felt or any other pliant substance utilizable in the art.

An important purpose of the stiffening core 6 is to preserve the useful shape of the pad 4 notwithstanding the innumerable shocks due to the ever repeated impacts of the type bars that recoil at each operative stroke when typewriting. As the core 6 has a smaller cross sectional shape than the inner section of the tubular pad 4, it provides between their contiguous surfaces a free space or clearance which contributes to give to the pad adequate suppleness and resiliency.

As will be understood, in order to eliminate any noise caused by the impact of the type bars on their carrying surface, it is necessary that somehow the latter should become momentarily distorted and that the energy which is thus imparted to said carrying surface should not be given back to the type bars but absorbed as completely as possible by its resilient distortion and by its resumption of its normal shape.

Owing to the fact that the improved pad is supported and held at a few points only, the aforesaid requirement is primarily fulfilled because any local distortion of the pad is converted into a longitudinal distortion which is evenly distributed throughout its length or at least over an appreciable length on both sides of the impacting type bar. Such a distortion absorbs a substantial proportion of the energy of said type bar which cannot therefore be imparted back to said bar. Furthermore by providing a free clearance or space inside the pad, such an action is still further enhanced because to the longitudinal distortion thus evenly distributed there is added an evenly distributed transverse distortion.

A cushioning pad having the aforesaid structure may be adapted either to new typewriters or to existing typewriters for example as a substitution for the type bar carrier lining of known form.

The constructional details may vary without departing from the scope of the subjoined claims.

What is claimed is:

1. A shock and sound absorbing unit for cushioning the rebound of the type bars of typewriters, comprising, an attaching plate having a horizontally straight bottom portion provided at its corners with fastening receiving openings and adapted to be secured to the typewriter frame in a vertical plane, said plate having its upper portion formed with an arcuate edge, cushion supporting elements formed integrally with the plate at the ends of the arcuate upper edge and offset rearwardly of the vertical plane of the body, an intermediate cushion supporting member formed integrally with the lower portion of the arcuate edge of the plate and offset forwardly of the vertical plane of the body, and an arcuate cushioning pad mounted on said rearwardly and forwardly extending cushion supporting elements respectively at the ends and intermediate portion of the arcuate edge of the plate thereby to support the cushioning pad at an oblique angle to the vertical plane of the plate.

2. A shock and sound absorbing unit for cushioning the rebound of the type bars of typewriters according to claim 1, wherein the cushion supporting elements at the upper ends of the arcuate edge of the plate are in the form of eyes embracing the ends of the cushioning pad.

3. A shock and sound absorbing unit for cushioning the rebound of the type bars of typewriters according to claim 1, wherein the cushion supporting elements at the intermediate part of the arcuate edge include a trough-shaped part for receiving the bottom portion of the cushioning pad.

4. A shock and sound absorbing unit for cushioning the rebound of the type bars of typewriters according to claim 1, wherein the arcuate cushioning pad is tubular and has an internal stiffening rod of the same radius of curvature as the bore of the tubular member and is adhesively secured thereto, and wherein the outer surface of the tubular cushioning pad is adhesively secured to the said end and intermediate cushioning supporting members.
